UNITED STATES PATENT OFFICE.

CARL H. KINDL, OF ANDERSON, INDIANA, ASSIGNOR, BY MESNE ASSIGNMENTS, TO DELCO-REMY CORPORATION, OF DAYTON, OHIO, A CORPORATION OF DELAWARE.

ENGINE-STARTING APPARATUS.

Application filed December 31, 1925. Serial No. 78,564.

This invention relates to starting apparatus for internal-combustion engines, and more particularly to apparatus comprising an electric motor, a spirally-splined shaft 5 driven by the motor, and a pinion which is threaded on the shaft and is moved endwise by a pedal into partial engagement with the gear of an engine to be started. The motor is operated to turn the threaded shaft in a 10 direction which will cause the pinion to be moved into full engagement with the engine gear and against a stop. Then the pinion will turn with the shaft to drive the engine gear in order to crank the engine. After 15 the engine becomes self-operative, the pinion will be demeshed automatically by reason of a screw-thread connection of the pinion with the motor.

One of the objects of the present invention 20 is to provide means for controlling the motor so that it will operate initially slowly in order to facilitate meshing with the gears manually and with low power sufficient to cause the motor to thread the pinion into full 25 engagement with the engine gear, and finally so that the motor will operate with full power only after the pinion is in substantially full engagement with the engine gear. In this way, the liability of breakage of gear 30 teeth or other parts of the starting apparatus is eliminated.

Further objects and advantages of the present invention will be apparent from the following description, reference being had to 35 the accompanying drawings, wherein a preferred form of the present invention is clearly shown.

In the drawings:

Figs. 1, 2, 3 and 4 are side views partly in 40 section of a starting apparatus embodying the present invention and showing the apparatus in three different positions of operation.

Fig. 5 is a sectional view on the line 5—5 45 of Fig. 1.

Fig. 6 is a sectional view on the line 6—6 50 of Fig. 1.

Fig. 7 is a fragmentary side view in the direction of the arrow 7 in Fig. 6.

In the drawings, 20 designates a field 55 frame of an electric motor which is supported by a gear housing 21 which is adapted to be attached to the frame of an engine to be started. The housing 21 provides a bear-

ing 22 for the armature shaft 23 of the motor, the other bearing being provided with an end frame (not shown), secured to the other end of the motor frame 20. The shaft 23 supports an armature 24 and is provided with a shouldered portion 25 and with a spirally-splined portion 26. A thrust collar 27 is secured to a shaft by pin 28 and bears against a thrust washer 29. This in turn bears against a finished surface 30 of the gear housing 21. A pinion 31 is threadedly connected with the splines 26 so as to move endwise along the shaft 23 and turn with the shaft after the pinion has been moved against the collar 27. In order to move the pinion endwise, there is provided a sleeve 32 having spaced flanges 33 defining an annular groove 34. The groove 34 receives the arms 35 of a bifurcated pinion-shifting lever 36 having a yoke 37. The sleeve 32 is connected by flanged tubular members 38 and 39 joined by flange 40 and fingers 41. Members 38 and 39 enclose a spring 42 tending to separate the gear 31 from the sleeve 32, but separation is prevented by the flange 43 of member 42 engaging a ring 44 carried by the gear 31. 70 Therefore, the spring 42 transmits motion toward the right from the sleeve 32 to the gear 31; and the members 44, 39 and 38 transmit motion toward the left from said sleeve to said gear.

The mechanism for moving the sleeve 32, 85 includes a pedal 45 connected by pedal rod 46 with a pedal lever 47 which carries a stud 48 providing a pivot for a latch 49 which is adapted to be received by a notch 50 in one arm 35 of lever 36. A spring 51 tends to maintain the latch 49 in this position, one end of spring 51 being received by a groove 52 in a stud 53 carried by lever 47, the other end bearing against an ear 54 of latch 49, 90 and the intermediate portion being coiled around stud 48.

Means for disconnecting the lever 47 from the lever 36 includes a rod 55 guided by a bearing 56 attached by a screw 57 to the motor housing 20. The rod 55 has a head 58 engageable with the ear 54 of latch 49, and a spring 59 located between the bearing 56 and the head 58 resists movement of the rod 55 due to movement of the pedal 45 downwardly. The spring 59, therefore, 100 tends to move latch 49 out of engagement with the lever 36, but the engaging surfaces 105

of said latch and lever are constructed and arranged so that friction between said surfaces will resist separation of the latch and lever until the motor is operated to move the 5 gear 31 into complete mesh with a gear 60 of the engine to be started. When the gear 31 is moved endwise into mesh with the gear 60, due to the operation of the motor independent of the pedal 45, this pressure will be 10 relieved so that by the time that the motor gear 31 is in full engagement with the engine gear 60, as shown in Fig. 3, the latch 49 will be entirely disengaged from the lever 36. This mechanism has been provided in order 15 that the pinion may be demeshed automatically, regardless of failure of the operator to release the pedal 45.

By a controlling apparatus associated with the pedal lever 47 and with the pinion-shifting lever 36, the motor is caused to turn slowly at first to facilitate meshing the pinion 31 with the gear 60, and to operate with low power sufficient only to cause the pinion to be threaded from the partly-meshed position in Fig. 2 to the fully-meshed position shown in Fig. 3. Then the controller is operated automatically when the pinion has moved into substantially fully-meshed position for causing the motor to operate with 20 full power to crank the engine. After the engine becomes self-operative, the pinion is demeshed and is returned to the position shown in Fig. 1, although the pedal lever 47 may remain in the position shown in Fig. 3. 25 A spring 61, having an intermediate portion coiled upon the rod 62 which supports the levers 47 and 36 and having its end portions bearing respectively against the housing 21 and against the lever yoke 37, causes the lever arms 35 to be urged in a clockwise direction so that the sleeve 32 will be maintained normally against the shoulder 25. After the pedal 45 is released, a spring 63 located between the pedal 45 and a cup-shaped member 64 attached to the floorboard 65 of the vehicle causes the pedal 45 and lever 47 to return to the position shown in Fig. 1. During the return movement of the lever 47, the latch 49 moves over the hub 50 of the lever arm 35 of the lever 36 and snaps into position within the notch 50, as shown in Figs. 1 and 7.

The apparatus for controlling the operation of the motor, comprises a plurality of switches independently operated and housed within a switch case 70 which is mounted upon the motor frame 20. The top wall of the switch case insulatingly supports a terminal bolt 71 connected with a plate providing contacts 72 and 73. The bolt 71 is connected by resistance element 74 with a switch contact 75 connected with the field winding 76 of the motor. As shown diagrammatically in Fig. 1, the field 76 is connected by a brush 77 with the armature wind-

ings 78 connected by a brush 79 with ground 80. A contact 81 is connected with a battery 82 by a terminal strap 83.

The switch for short-circuiting the resistance 74 comprises the stationary contacts 73 and 75, and a movable bridging contact 84 which is insulatingly supported and is slideable upon a rod 85 having a collar 86. Rod 85 is threadedly engaged by a rod 87, provided with a collar 88. A spring 89, bearing against the collar 86, normally urges the contact 84 toward the collar 88.

The main switch by which the motor is initially connected with the current source through the resistance 74 comprises contacts 80 81 and 72 and a movable bridging contact 90 insulatingly supported by a sleeve 91 and movable endwise therewith. Sleeve 91 normally bears at one end against the collar 86 on the rod 85 and the other end of the sleeve 91 is provided with a nut 92 for receiving a lever 93 which is pivoted at 94 upon a bracket 95 which may be a part of the switch case 70. A spring 96, engaging the nut 92 and one end of a sleeve 97 for supporting the sleeve 91 and rod 85, tends to maintain the contact 90 out of engagement with contacts 81 and 72.

The closing of the resistance short-circuiting switch by moving contact 88 into engagement with contacts 73 and 75, is controlled only in response to movement of the pinion 31. This is accomplished by connecting the rod 85 with the lever 36 by providing the rod 85 with a hook 98 and the lever 36 with a slot 99 for receiving the hook.

The main switch contact 90 is moved into engagement with contacts 81 and 72 in response to the movement of the lever 47. 105 This is accomplished by providing the lever 47 with a pivotally-mounted block 100 having a hole for loosely receiving and guiding a rod 101 having an eye end 102 connected with the lever 93. A compression spring 110 103 is located between a flange 104 on the rod 101 and the block 100.

Downward movement of the pedal 45 causes the main switch to be closed by moving the contact 90 into engagement with the contacts 72 and 81. This causes the motor to operate slowly with relatively low power so as to facilitate engagement of the pinion 31 with the engine gear 60, as shown in Fig. 2. Now, although the operator may apply pressure continually to the pedal 45, this pressure will not cause the resistance short-circuiting switch to be closed, but will simply assist meshing the pinion 31 while the motor is also operating to cause the pinion 125 to be threaded into mesh.

Fig. 3 shows the condition of the apparatus when the main switch and the short-circuiting switch are both closed and the motor operates with full torque to crank the 130

engine. The short-circuiting switch is closed just slightly before the right end face of the pinion 31 strikes the stop collar 27. At this time, the latch 49 is disengaged from 5 the lever 36, so that the condition of the pinion 31 is entirely out of control of the operator and, likewise, the condition of the resistance short-circuiting switch. Therefore, when the engine becomes self-operative, 10 the pinion 31 will be moved endwise away from the gear 60 and the short-circuiting switch will be opened, although the operator continues to press down the pedal 45. The automatic movement of the pinion 15 31 to normal position is accompanied by a movement of rod 85, causing the collar 88 to move the contact 84 away from contacts 73 and 75.

It is apparent, therefore, that the present 20 starting apparatus removes from the direct control of the operator, the closing of a circuit which would cause the motor to operate with full power. Therefore, no matter how rapidly and forcibly the pedal 43 is 25 depressed, the motor will not operate with full power until the apparatus is in condition for full power to be applied, that is, not until the starter gears are substantially in mesh. The present apparatus removes 30 from the control of the operator, the low-resistance circuit connection between the battery and the motor in addition to the demeshing of the gearing after the engine becomes self-operative. Therefore, the motor 35 armature will not be rotated at an excessively high speed, and the battery will not be discharged except at low rate in case the operator should fail to release the operating handle or pedal.

40 Fig. 4 shows the condition of the apparatus if the pinion should be fully meshed with the engine gear and the engine should fail to become self-operative. The resistance short-circuiting contacts 73, 84 and 75 would 45 remain engaged, but release of the pedal lever 47 would permit separation of contact 90 from contacts 72 and 81. Thus, the battery could be disconnected from the apparatus, although the pinion 31 should be meshed 50 with the engine gear 60 and the engine should fail to start and automatically demesh the pinion.

While the form of embodiment of the present invention as herein disclosed, constitutes a preferred form, it is to be understood that other forms might be adopted, all coming within the scope of the claims which follow.

What is claimed is as follows:

60 1. Engine starting apparatus comprising, in combination, a motor including a frame, means for connecting the motor with the gear of an engine to be started and including a pinion movable into mesh with the 65 gear and driving connections whereby oper-

ation of the motor will complete the meshing of the pinion with the gear after meshing has been initiated and whereby the pinion will be automatically demeshed when the engine becomes self-operative, a housing 70 for the connecting means, manually-operated means for moving the pinion into partial engagement with the gear, a motor control mounted upon the motor frame and actuated by said manually operable means 75 for causing the motor to operate with low power to complete the meshing of the pinion with the gear, means for disconnecting the manual means from the pinion after the pinion has been meshed, and a second motor 80 control mounted upon the motor frame and actuated automatically when the pinion has been substantially fully meshed with the gear for causing the motor to operate with high power to crank the engine and rendered 85 ineffective when the pinion is automatically demeshed, whereby the pinion will be demeshed and high-power operation of the motor will cease after the engine becomes self-operative regardless of the status 90 of the manually-operated means.

2. Engine starting apparatus comprising, in combination, an electric motor including a frame, means for connecting the motor with the gear of an engine to be started and including a pinion and driving connections 95 whereby operation of the motor will complete the meshing of the pinion with the gear after meshing has been initiated and whereby the pinion will be automatically 100 demeshed when the engine becomes self-operative, a housing for the connecting means, manually-operated means for moving the pinion into partial engagement with the gear, a motor circuit having a switch mounted upon the motor frame and rendered operative by said manual means for causing the motor to operate with low power to complete the meshing of the pinion with the gear, means for disconnecting the manual means from the pinion after the pinion has been meshed with the gear, and a motor circuit having a switch mounted upon the motor frame and rendered operative in response to the low-power operation of the 105 motor for causing the motor to operate with high power to crank the engine when the pinion is substantially fully meshed with the gear and rendered inoperative when the pinion is automatically demeshed, whereby 110 the pinion will be demeshed and high-power operation of the motor will cease after the engine becomes self-operative regardless of the status of the manually-operated means.

3. Engine starting apparatus comprising, 115 in combination, an electric motor including a frame, a spirally-splined shaft driven by the motor, a pinion on the shaft and driven through said splines and movable endwise into mesh with a gear of the engine to be 120 125 130

started, a housing for the shaft and pinion, manually-operated means for partly meshing the pinion and gear, a switch mounted upon the motor frame and actuated by the 5 manually operable means for causing the motor to operate with low power to complete the meshing by driving the splined shaft, means for automatically disconnecting the manual means from the pinion after the 10 pinion has been meshed with the gear, and a motor circuit having a switch mounted upon the motor frame and rendered operative when the pinion is substantially in full mesh with the gear for causing the motor 15 to crank the engine and rendered inoperative when the pinion is automatically demeshed, whereby the pinion will be demeshed and high-power operation of the motor will cease after the engine becomes 20 self-operative regardless of the status of the manually-operated means.

4. Engine starting apparatus comprising, in combination, an electric motor, a spirally-splined shaft driven by the motor, a pinion 25 on the shaft and driven through said splines, a pinion-shifting lever for moving the pinion endwise into mesh with a gear of the engine to be started, a pedal-operated lever, means normally connecting the levers, a circuit 30 including a switch operated by the pedal lever for effecting low-power operation of the motor to complete the meshing of the pinion and gear, means for automatically disconnecting the pedal operated lever from the pinion shifting lever after the pinion has 35 been meshed with the gear, and a circuit including a switch operated by the pinion shifting lever when the pinion is substantially in full mesh with the gear for causing the motor to crank the engine, said last- 40 mentioned circuit being rendered inoperative when the pinion is automatically demeshed whereby the pinion will be demeshed and high-power operation of the motor will 45 cease after the engine becomes self-operative regardless of the status of the manually-operated means.

5. Engine starting apparatus comprising, in combination, an electric motor, means for 50 connecting the motor with the gear of an engine to be started and including a pinion and driving connections whereby operation of the motor will complete the meshing of the pinion with the gear after meshing has 55 been initiated and whereby the pinion will be automatically demeshed when the engine becomes self-operative, a pinion shifting lever for causing the pinion to move into mesh with the gear, a pedal operated lever, 60 means normally connecting the levers, means for automatically disconnecting the pedal operated lever from the pinion shifting lever after the pinion has been meshed with the gear, a motor controller operated by the 65 pedal member for causing the motor to op-

erate to complete the meshing of the pinion with the gear, and a motor controller automatically actuated by the pinion shifting lever for causing the motor to operate with high power to crank the engine when the 70 pinion is substantially fully meshed with the gear, said last-mentioned controller being rendered inoperative when the pinion is automatically demeshed whereby the pinion will be demeshed and high-power operation 75 of the motor will cease after the engine becomes self-operative regardless of the status of the manually-operated means.

6. Engine starting apparatus comprising, in combination, an electric motor including 80 a frame, means for connecting the motor with the gear of an engine to be started and including a pinion and driving connections whereby operation of the motor will complete the meshing of the pinion with the gear after meshing has been initiated and whereby the pinion will be automatically demeshed when the engine becomes self-operative, a housing for the connecting means, 85 manually-operated means for moving the pinion into partial engagement with the gear, a motor circuit having a switch provided with an endwise movable actuating rod operated upon by said manual means for causing the motor to operate with low power to complete the meshing of the pinion with the gear, means for disconnecting the manual means from the pinion after the pinion has been meshed with the gear, and a motor 90 circuit having a switch provided with an endwise movable actuating rod concentric with the first mentioned switch rod and operated upon in response to the low-power 95 operation of the motor for causing the motor to operate with high power to crank the engine when the pinion is substantially fully meshed with the gear and rendered inoperative when the pinion is automatically demeshed, whereby the pinion will be demeshed and high-power operation of the motor will 100 cease after the engine becomes self-operative 105 regardless of the status of the manually-operated means.

7. Engine starting apparatus comprising, in combination, an electric motor, a spirally-splined shaft driven by the motor, a pinion on the shaft and driven through said splines, a pinion-shifting lever for moving the pinion endwise into mesh with a gear of the engine to be started, a pedal-operated lever, 115 means normally connecting the levers, a circuit including a switch provided with an endwise movable actuating rod operated by the pedal lever for effecting low-power operation of the motor to complete the meshing of the pinion and gear, means for automatically disconnecting the pedal-operated lever from the pinion shifting lever after the pinion has been meshed with the gear, and 120 a circuit including a switch having an end- 125

- wise movable actuating rod concentric with the first mentioned switch actuating rod and operated by the pinion shifting lever when the pinion is substantially in full mesh with
- 5 the gear for causing the motor to crank the engine, said last mentioned circuit being rendered inoperative when the pinion is automatically demeshed whereby the pinion
- will be demeshed and high-power operation 10 of the motor will cease after the engine becomes self-operative regardless of the status of the manually-operated means.
- In testimony whereof I hereto affix my signature.

CARL H. KINDL.
